SEWING MACHINE

French Eugene Smith, Akron, Ohio, assignor to White
Sewing Machine Corporation, Lakewood, Ohio, a cor-
poration of Delaware

Application October 20, 1955, Serial No. 38,490

Term of patent 14 years

(Cl. D70—1)

FIG. 1

FIG.2

FIG.3

Fig. 1 is a front perspective view of a sewing machine embodying my design and is taken looking from the front left hand end of the sewing machine.

Fig. 2 is a perspective view of the sewing machine shown in Fig. 1, but is taken looking from the front right hand end thereof with a portion broken away for convenience of illustration, and

Fig. 3 is a rear perspective view of the sewing machine shown in Figs. 1 and 2.

I claim:

The ornamental design for a sewing machine, as shown.
